UNITED STATES PATENT OFFICE.

SAMUEL L. ALLEN, OF MOORESTOWN, NEW JERSEY.

CULTIVATOR.

No. 828,172.

Specification of Letters Patent.

Patented Aug. 7, 1906.

Application filed March 29, 1905. Serial No. 252,659.

To all whom it may concern:

Be it known that I, SAMUEL L. ALLEN, a citizen of the United States, and a resident of Moorestown, county of Burlington, State of New Jersey, have invented certain new and useful Improvements in Cultivators, of which the following is a full, clear, and complete disclosure.

The object of my invention is to produce such a construction in cultivators that the same may be adapted to a great variety of uses, and also that the same may be more easily adjustable and the parts more firmly held in position than heretofore has been possible.

Briefly, my invention comprises a gang-frame having a rear tool-carrying bar to which the tools are adjustably clamped, said tool-carrying bar having adjustable end portions which may be moved inward and outward to provide a greater or less width to the whole machine-frame, while at the same time I would provide means for holding said adjustable parts firmly and rigidly in position, but allowing the same to be quickly and easily adjusted.

My invention also comprises means for lowering and raising and fixing the height or position of the machine-frame in relation to the running-gear and the surface of the ground.

For a full, clear, and exact description of this embodiment of my invention reference may be had to the following specification and to the accompanying drawings, forming a part thereof, in which—

Figure 1 is a side elevation of my improved cultivator. Fig. 2 is a plan view thereof, the seat being shown in dotted lines. Fig. 3 is a longitudinal sectional view taken substantially upon the line 3 3, Fig. 2. Fig. 4 is a perspective view of the details of the mechanism for adjusting the height of the machine-frame and tools carried thereby in relation to the surface of the ground. Fig. 5 is a perspective view of the details of the extension to the tool-carrying bar, and Fig. 6 is a plan view of a modified form of construction for giving a greater effective width to the cultivator-frame without the use of extensions on the tool-carrying-bar.

Referring to the drawings, the numeral 1 indicates the main axle upon which the supporting-wheels 2 2 are adapted to rotate. The wheels 2 2 may be held in position upon the axle and in a suitable manner, but I have

preferably employed the split-pin and collar construction, as shown, the collars being made adjustable upon the axle by means of a series of holes 1', through which the split pin 60 may pass. Rigidly attached to the end of each axle or formed integrally therewith and extending at substantially right angles thereto are connecting bars or links 3, which are adapted to assume any angle in relation to 65 the horizontal. To the ends of the links 3 are pivoted the two parallel ends of a substantially rectangular frame 4 by means of bolts 5. The forward bar of the frame 4 is preferably slightly offset forwardly at its central portion, as indicated at 6, so as to engage the tongue at a point somewhat in advance of the other portions of the frame. The rear side of this frame 4 is preferably formed by a single bar 7, which is attached to the end bars 75 of the frame 4 by means of bolts 8, which have their heads countersunk in the bar 7, so as to not obstruct or interfere with the other parts of the frame, hereinafter to be mentioned. Said bar 7 is provided at its ends with laterally-extending lips or flanges 7'. The end bars of the frame 4 are preferably curved downwardly and then upwardly, so as to engage the rear side of the bar 7, as indicated in dotted lines in Fig. 5, thus forming a head 85 adapted to be held in position by means of the bolt 8. Suitable brace-rods 9 of a shape similar to the end bars of the frame 4 are placed at points intermediate the ends of said frame to stiffen the frame transversely and 90 to more evenly distribute the pull of the draft mechanism upon the entire tool-bar.

To the tool-bar 7 is attached a pair of angle irons 10, the inwardly-extending portions of which are enlarged and extend parallel and vertically at a sufficient distance apart to provide space for the reception of the end of the tongue 11, said angle-irons being provided with a series of holes 12 to allow of adjustment of the angle of the tongue 11 in relation 100 to the frame of the machine, the tongue 11 being provided with a hole through which is adapted to pass a bolt 13 to connect the tongue with the angle-plates 10. The tongue 11 is held in position above the forward bar of the frame 4 and above its central portion 6 by means of a U-shaped metallic strap 14, which is bolted to the front bar 6 and is connected with the tongue 11 by means of a bolt 15. This construction practically makes the tongue a part of the frame, particularly in relation to the lifting mechanism hereinafter 105

to be referred to. As means for attaching the draft mechanism to the frame of the machine I provide a downwardly-projecting part 16, consisting of two parallel bars connected 5 at their lower ends and which are bolted at their upper ends to the tongue 11 by means of a bolt 17. A brace 18 connects the lower end of the part 16 with the rear portion of the tongue 11. The parallel bars constituting 10 the part 16 are provided with a series of holes 19, by means of which the height of the point of pull of the draft mechanism may be varied. The draft mechanism may consist of the usual whiffletree 20 and the doubletree 21.

15 The ends of the rear tool-bar 7 are provided with a pair of adjustable extensions 22, which are curved transversely at their outer ends to form arcs, as indicated at 23, and provided with a pair of lips or flanges 24, between 20 which pass the forward brace-bars 25, said brace-bars being provided with longitudinal slots 26, adapted to engage bolts 27, carried by the extension-bars 22. The forward end of each brace-bar 25 is pivoted in relation to 25 the frame 4 by means of a U-shaped block 28, which is bolted to the end of the frame 4 and which is provided in its lower end with a slot into which passes the end of said brace-bar 25, said bar being retained therein by a pin or bolt 29. The inner end of the extension-bar 22 is clamped to the end of the tool-bar 7 by means of a U-shaped clamp 30, which also holds the tool-standard 31 rigidly in position. The lips 7' prevent any upward movement of 35 the extensions 22 due to forcing the blades into the ground. The U-shaped clamps 30 consist of U-shaped metallic straps having slots in their outer ends and provided with a screw or bolt 32 for drawing the tool-standard 40 31 firmly against the tool-bars. The clamps which secure the other tool-standard to the tool-bar are substantially the same as that just described, with the exception that the arms of the U-shaped strap are somewhat 45 shorter, as they do not have to embrace the extension-bars 22.

It will now be evident that in the adjustment of the extension-bars 22 the curved portion of the brace 25 may slide upon the 50 curved ends of the bars 22, and the variation in the length of the hypotenuse of the triangle formed by the frame 4, extension 22, and brace 25 is provided for, while at the same time the parts may be clamped rigidly and 55 accurately in position.

The means for raising and lowering the tool-frame consist of the following parts: To the axle 1 is attached a U-shaped bar 33, which terminates in transversely-extending 60 foot-pieces 34. Upon each of the sides of said U-shaped bar is riveted a plate 35, which extends substantially at right angles to said sides and constituting therewith a bell-crank lever. At the upper ends of these plates 35 65 are pivoted two bars 36, which unite midway

of their lengths to form a hand-lever 36'. The bars 36 extend each side of the tongue 11 to the points where they are attached to the plates 35 and are held in position relatively to each other above the tongue by means of the 70 bolts 37 and 38, the bolt 38 being long enough to form a tie between the diverging portions of the bars 36. To each of the bars 36 and midway between the points where they are attached to the plates 35 and the point of convergence or union are bolted or riveted angle-plates 39, which carry at their lower ends a roller 40, which is adapted to bear underneath the tongue 11 and have a longitudinal movement thereon. 75

80 For the purpose of holding the lever 36' in its correct relation to the tongue 11 and to determine the depth of the cut when the blades are in their operative position in the ground I provide a screw-threaded rod 41, which is 85 journaled in a block 42, secured between the diverging portions of the bars 36 by the bolt 37, the said block 42 having a screw-threaded hole therein and said rod 41 terminating in a crank-handle 43. The lower end of the 90 screw-threaded rod 41 rests upon a grooved block 44, carried by the tongue 11 and preferably located between the upper ends of the depending bars 16.

It will now be seen that the whole frame 4 95 will be supported upon the axle 1 through the plates 35 and the bars 36 and lever 36', since the tongue 11 is supported upon the roller 40 and held in its requisite position in relation thereto by means of the hand-screw 41. 100 However, the weights supported by these parts are not affected by the draft upon the machine, as such draft is substantially in a straight line with the tool-standard 31 and the blades 45, carried thereby, and although 105 the main frame is fixed in position by comparatively light parts and by the lever 36, yet there is no great strain upon them and the only actual weight that they have to support is that of the operator and the weight of 110 the gang-frame and connecting parts.

When it is desired to raise the blades from the ground by elevating the gang-frame, the feet of the driver or operator are placed upon the foot-levers 34 and the lever 36' is grasped 115 by his hand. Then in pushing downwardly with the feet and pulling upwardly with the hand the roller 40 is raised and travels on the under side of the tongue 11 as the blades at 35 are rotated with the axle 1. The roller 40 120 on being raised carries with it the tongue 11, and as the latter is fixed in relation to the main frame said main frame must also be raised, carrying with it the tool-standard and tools or blades.

When the gang-frame is once raised, it is 125 only necessary to hold the lever 36' in its new position in order to keep the blades of the cultivator free from the ground. This is done by the following means: To the seat- 130

support 46, which is preferably attached to the tongue 11, is bolted two angle-irons 47, to which is pivoted a bar or tie-rod 48, having in its under side an inclined slot or notch 49.

5 This slot 49 is adapted to engage the bolt 38 or other suitable projection when the lever 36' is in its highest or raised position.

In Fig. 6 I have shown a modified form of means for securing the outer tool-standard 10 beyond the extreme limit of the main frame. In this modification the extension-bars 22 are omitted and the outer tool-standard is secured directly to the end of the side frame-bar of the frame 4, suitable washers or separators, having inclined ends 50, being interposed between the side of the frame and the tool-standard. By rotating the washers or separators the amount the outer blades project beyond the frame may be varied.

20 Having thus described my invention, I do not wish to be understood as being limited to the exact details of form and arrangement of parts of the device herein set forth, for changes may be made in the form, arrangement, and proportion of parts without departing from the spirit and scope of my invention; but

What I claim, and desire to protect by Letters Patent of the United States, is—

30 1. In a cultivator, a tool-carrying bar fixed to the main frame, an extension adjustable longitudinally of said bar, and a brace-bar pivoted to said frame, the said extension and brace-bar being adjustably fastened together, the engaging surface of the one being concentric with the engaging surface of the other.

2. In a cultivator, a tool-carrying bar fixed to the main frame, an adjustable extension 40 arranged longitudinally of said bar, and a brace-bar pivoted to said frame, the said extension and brace-bar being adjustably fastened together by a slot-and-bolt connection, the engaging surface of the one being concentric with the engaging surface of the other.

45 3. In a cultivator, the combination with a gang-frame, running-gear and means for raising the gang-frame connected to the running-gear, of a tool-bar fixed to the gang-frame, adjustable extensions arranged longitudinally of said bar and brace-bars pivoted to the frame and engaging said extensions by a slot-and-bolt connection.

4. In a cultivator, the combination with a 55 gang-frame, running-gear, and means for raising the gang-frame connected to the running-gear, of a tool-bar fixed to the gang-frame, adjustable extensions arranged longitudinally of said bar, and brace-bars pivoted to the frame, the said extension and brace-bars being adjustably fastened together, the engaging surface of the one being concentric with the engaging surface of the other.

5. Means for fastening a tool-standard to a 65 tool-bar, comprising a U-shaped metallic

strap having an aperture in the base thereof and alined apertures adapted to receive the tool-standard, and a screw-threaded bolt passing through the said aperture in the base of the strap, to draw said standard against 70 said tool-bar.

6. In a cultivator, a tool-carrying means, comprising a portion fixed to the main frame, and having a curved end portion, said curved portion being provided with two marginal 75 longitudinal flanges, and a lateral brace connected to the main frame and provided at its rear end with a curved portion having an opening, and a bolt or similar means for retaining the end of said bar between said flanges and for clamping the same to said curved portion.

7. In a cultivator, a tool-carrying bar, comprising a portion fixed to the main frame, an adjustable extension thereof having a straight 85 portion and a curved end portion, and a lateral brace attached to the main frame and to said curved portion.

8. In a cultivator, a tool-carrying bar, comprising a portion fixed to the main frame, an 90 extension thereof, comprising a separable bar having a straight and a curved portion, and a lateral brace pivoted to the main frame and adjustably clamped to said curved portion.

9. In a cultivator, a tool-carrying bar, comprising a portion fixed to the main frame, a 95 separable extension thereof having a straight portion and a curved end portion, and a forwardly-extending brace pivoted to the main frame and adjustably retained in a longitudinal 100 guide provided in said curved portion.

10. In a cultivator, a tool-carrying bar, comprising a portion fixed in relation to the main frame, a separable extension thereof having a straight portion and a curved end 105 portion, said curved end portion being provided with two longitudinal marginal flanges, and a lateral brace pivoted to the main frame and having its opposite curved end attached to said curved portion so as to be adjustably 110 retained between said flanges.

11. In a cultivator, a tool-carrying bar comprising a portion fixed to the main frame, an adjustable extension therefor, one of said parts being provided with a lip or flange to 115 resist the pressure due to the downward thrust of the tools or blades carried by said extension, and a clamp for connecting said bar and extension.

12. In a cultivator, a tool-carrying bar, 120 fixed to the main frame, an adjustable extension therefor, said bar being provided with a lip or flange on one side thereof adjacent its upper edge to resist the pressure due to the downward thrust of the tools or blades 125 carried by said extension, and a clamp for connecting said bar and extension.

13. In a cultivator, a tool-carrying bar, fixed to the main frame, a separable extension thereof having a straight portion and a 130

- curved end portion, said curved portion being provided with two marginal longitudinal flanges, and a lateral brace pivoted to the main frame and provided at its rear end with 5 a curved portion having a longitudinal slot, and a bolt or similar means for retaining the slotted end of said bar between said flanges and for adjustably clamping the same to said curved portion.
- 10 14. In a cultivator, a gang-frame, running-gear for supporting said gang-frame, a lever pivoted in relation to said running-gear and having a slidable bearing for supporting said gang-frame and a screw engaging said lever 15 and a part of the frame for determining the height of the gang-frame when in operative position.
- 15 14. In a cultivator, a gang-frame, running-gear for supporting said gang-frame, a lever pivoted in relation to said running-gear and having a slidable bearing for supporting said gang-frame, and a screw-threaded rod carried by said lever and engaging a part of said frame for fixing the position of said lever to 20
- determine the height of the gang-frame when 25 in operative position.
16. In a cultivator, a gang-frame, running-gear for supporting said gang-frame, a lever pivoted in relation to said running-gear and having a slidable bearing for supporting said 30 gang-frame, and a hand-crank having a screw-threaded shaft carried by said lever for fixing the position of the same to determine the height of the gang-frame when in operative position.
17. In a cultivator, a gang-frame, running-gear for supporting said gang-frame, a lever pivoted in relation to the running-gear and having a slidable bearing for supporting said gang-frame, and means to determine the 40 height of the gang-frame when in operative position.

In witness whereof I have hereunto set my hand this 27th day of March, A. D. 1905.

SAML. L. ALLEN
